UNITED STATES PATENT OFFICE.

GUSTAF DAVID SUNDSTRAND, OF ROCKFORD, ILLINOIS, ASSIGNOR TO ROCKFORD TOOL COMPANY, OF ROCKFORD, ILLINOIS, A CORPORATION OF ILLINOIS.

LATHE.

Application filed June 11, 1920. Serial No. 388,211.

To all whom it may concern:

Be it known that I, GUSTAF DAVID SUNDSTRAND, a citizen of the United States, residing at Rockford, in the county of Winnebago and State of Illinois, have invented 5 certain new and useful Improvements in Lathes, of which the following is a specification.

My invention relates to lathes of the general type illustrated in Patent No. 1,325,424 issued December 16, 1919, and more specifically to an improved rear tool and transmission for automatically actuating the same.

15 One of the objects of the invention is to provide an improved rear tool carriage embodying, in a unitary structure, a complete transmission for actuating the rear tool in either direction upon movement of the front 20 carriage in either direction.

Another object is to include means for changing the speed ratio between the movement of the front and rear tool in the transmission carried by the rear tool carriage.

25 Further objects and advantages of my invention will become apparent as the description proceeds.

In the accompanying drawings, Figure 1 is a perspective view of a complete lathe 30 equipped with a rear tool according to my invention. Fig. 2 is an end view of the lathe with the tail stock removed, the rear tool and its transmission being shown in section. Fig. 3 is a front view of the rear tool 35 and Fig. 4 is a detail section.

In the embodiment of my invention selected for illustration, the bed 10 carries ways 12 and 14, supporting the slidable front carriage 16 and another set of ways 18 and 20 supporting the rear carriage 22 which may be clamped in position by suitable blocks 24 and clamping screws 26. Any suitable or customary means for actuating the front carriage may be provided, as, for 45 instance, a drive shaft 28 operating gearing in a casing 30 to drive a pinion 32 meshing with a rack 34 mounted on the bed 10.

On the rear of the front carriage I mount 50 a rack 36 above which is placed a cover 38 to protect it from falling chips and dirt. Means for driving the rear tool from the rack 36 comprise a gear 40 on shaft 42, a second gear 44 on the upper end of shaft 46, a change gear 48 on the lower end of shaft

46, and a change gear 50 splined to the shaft 52 preferably formed integral with a bevel gear 54. Gears 40 and 44 may be protected by a cover 45 cooperating with the walls of the rear carriage casting to completely enclose the gears except for an opening 47 through which gear 40 projects to engage rack 36. The shafts 42 and 46 and the bevel gear 54 are, as clearly indicated in Fig. 2, supported in suitable bearings in the rear carriage. Knurled nuts 55 provide convenient means of holding the change gears 48 and 50 in place. They may be readily removed to slip the gears off and interchange or replace them with other gears.

An intermediate bevel 56 horizontally 70 journaled on shaft 58 meshes with the bevel gear 54 and with an opposing bevel gear 60 above it to drive the first and last bevel gears in opposite directions. A shaft 62 rotatable in the sleeve portions of the bevel 75 gears 54 and 60 carries a splined clutch collar 64 adapted to engage clutch teeth on the bevels 54 and 60 to drive the shaft in either direction. The clutch collar may be shifted by convenient means such as a pin 66 entering between flanges on the collar and carried by a shaft 68 mounted on an axis eccentric to the pin and rotatable by means of a suitable hand lever 70 outside the carriage casting. As the lathe may frequently be 80 used for a considerable length of time without disturbing collar 64, I prefer to provide means in the nature of a set screw 69 for locking shaft 68 and collar 64 in any desired position.

The shaft 62 carries a pinion 71 meshing with a rack 72 on the bottom of a cross slide 74 which carries another longitudinally 95 slide support 76 for the rear tool holder. Any suitable means for sliding the support 76 and clamping it in position may be employed. I have illustrated a pinion 78 carried by a shaft 80 having a handle 82 for rotation of the same, which pinion meshes with a rack 84 carried by the rear edge of 100 the support 76. A clamping screw 86 may be forced into engagement with the central part of the block 88 which engages the cross slide 74 with its heel 90 and overlies the rear portion of the support 76 at 92 to clamp it 105 firmly in longitudinally adjusted position. While I have illustrated a simple cross slide such

as that described in my copending application Serial No. 336,705, filed November 8, 1919, may be employed.

It will be apparent that the rear tool may be connected by the clutch collar 64 so as to feed in and perform a facing or cutting off operation during movement of the front carriage in either direction. While I have illustrated and described in detail the preferred embodiment of my invention, it should be clearly understood that the disclosure is merely for purposes of illustration and that many modifications and variations will naturally occur to those skilled in the art. I aim in the subjoined claims to cover all such legitimate variations and modifications.

I claim as my invention:

1. In a lathe, in combination, a front tool carriage, a rear tool carriage, a tool slide on said rear tool carriage, a rack extending along said front carriage, and transmission mechanism entirely mounted on and supported by said rear tool carriage and including a gear meshing with said rack, for reciprocating said rear tool slide upon longitudinal sliding movement of said front carriage.

2. In a lathe, in combination, a slidable front carriage, a rear carriage, a tool slide on said rear carriage and a transmission entirely supported by said rear carriage for driving said rear tool slide, said transmission including elements constantly engaged with said front carriage for actuation in either direction by longitudinal sliding movement thereof, elements permanently associated with said rear tool slide for reciprocating said slide, and means for disconnecting said last named elements from said first named elements.

3. In a lathe, in combination, a front tool carriage, a rear tool carriage, a tool slide on said rear tool carriage, a rack extending along said front carriage, and transmission mechanism entirely mounted on and supported by said rear tool carriage and including a gear meshing with said rack, for reciprocating said rear tool slide upon longitudinal sliding movement of said front carriage, said transmission including a reversing clutch.

4. In a lathe, in combination, a longitudinally slidable front carriage, a rear carriage, a tool slide on said rear carriage and a transmission entirely supported by said rear carriage for driving said rear tool slide, said transmission including elements constantly engaged with said front carriage for actuation in either direction by longitudinal sliding movement thereof, elements permanently associated with said rear tool slide for reciprocating said slide, and means for disconnecting said last named elements from said first named elements or connecting them to said first named elements for actuation in either direction.

5. In a lathe, in combination, a front tool carriage, a rear tool carriage, a tool slide on said rear tool carriage, a rack extending along said front carriage, and transmission mechanism entirely mounted on and supported by said rear tool carriage for reciprocating said rear tool slide upon longitudinal sliding movement of said front carriage.

6. In a lathe, in combination, a longitudinally slidable front carriage, a rear carriage, a tool slide on said rear carriage, and a transmission entirely supported by said rear carriage for driving said rear tool slide, said transmission including elements constantly engaged with said front carriage for actuation in either direction by longitudinal sliding movement thereof, elements permanently associated with said rear tool slide for reciprocating said slide, and means for connecting said last named elements to said first named elements for actuation in either direction.

7. In a lathe, in combination, a front tool carriage, a rear tool carriage, a tool slide on said rear tool carriage, and transmission mechanism entirely mounted on and supported by said rear tool carriage for moving said rear tool slide in either direction upon longitudinal sliding movement of said front carriage in a given direction.

8. In a lathe, in combination, a slidable front carriage, a rear carriage, a tool slide on said rear carriage, and a transmission entirely supported by said rear carriage for driving said rear tool slide, said transmission including elements constantly engaged with said front carriage for actuation in either direction by longitudinal sliding movement thereof, and means for connecting said elements to said slide for actuation thereof in either direction.

9. A lathe having, in combination, a front tool carriage, a rear tool carriage, a transversely-movable tool slide on said rear tool carriage, a rack extending along the rear edge of said front carriage, a rack extending along the tool slide, and a gear train entirely mounted on and supported by said rear tool carriage for connecting said racks.

10. In a lathe, the combination of a rear tool carriage, a sleeve rotatable on a vertical axis in said carriage and having a closed lower end, a bevel gear on said sleeve, a second bevel gear spaced from and rotatable on the same axis as said first mentioned gear, a third bevel gear meshing with each of the other gears, a vertical shaft rotatable in and supported by said sleeve and extending through the second mentioned gear, means for connecting said shaft to either gear, a tool slide and an operative connection between said shaft and slide, said sleeve terminating in a downwardly projecting shaft, a change gear on the lower end of the last-mentioned shaft below the carriage, a verti-

- cal shaft in said carriage forward of the first shaft, a change gear on the lower end of the third-mentioned shaft, and means to drive the third-mentioned shaft.
- 5 11. In a machine tool, in combination, a sleeve rotatable on a vertical axis and having a closed lower end, a bevel gear on said sleeve, a second bevel gear spaced from and rotatable on the same axis as said first mentioned gear, a third bevel gear meshing with each of said two first mentioned gears, a vertical shaft rotatable in and supported by said sleeve and extending through said second mentioned gear, means for connecting said shaft to either gear, a tool slide and an operative connection between said shaft and slide, said sleeve terminating in a downwardly projecting shaft adapted to receive a splined gear for the transmission 10 of power thereto.
12. In a machine tool, in combination, a slideable tool carriage, means for clamping said tool carriage in adjusted position, a tool slide on said tool carriage, and a transmission for driving said tool slide, said transmission including change gears and vertical shafts projecting below said carriage to receive said change gears on their projecting portions.
- 20 13. In a lathe, in combination, a slideable front carriage, a rear carriage, a tool slide on said rear carriage, and a transmission from said front carriage to said tool slide, said transmission including elements constantly engaged with and driven by motion of said front carriage, and a reversible connection between said elements and said slide.
14. In a lathe, in combination, a slideable front carriage, a rear carriage, a tool slide on said rear carriage, a transmission from said front carriage to said tool slide, said transmission including gearing constantly engaging said front carriage for actuation thereby, said gearing including change speed gears, and a reversible connection for driving said tool slide from said gearing.
15. In a lathe, in combination, a slideable front carriage, a rear carriage, a tool slide on said rear carriage, and a transmission from said front carriage to said tool slide, said transmission being mounted on said rear carriage and including elements constantly engaged with and driven by motion of said front carriage, and a reversible connection between said elements and said slide.
- 25 16. In a lathe, in combination, a slideable front carriage, a rear carriage, a tool slide on said rear carriage, a transmission from said front carriage to said tool slide, said transmission being mounted on said rear carriage and including gearing constantly engaging said front carriage for actuation thereby, said gearing including change speed gears, and a reversible connection for driving said tool slide from said gearing.
- 30 In testimony whereof, I have hereunto set my hand.

GUSTAF DAVID SUNDSTRAND.
